UNITED STATES PATENT OFFICE.

HOWARD ROY STACKS, OF PHILADELPHIA, PENNSYLVANIA, ASSIGNOR
TO GEO. V. CRESSON CO., OF PHILADELPHIA, PENNSYLVANIA.

CHANGE-SPEED GEARING.

No. 813,461.

Specification of Letters Patent.

Patented Feb. 27, 1906.

Application filed November 29, 1904. Serial No. 234,746.

To all whom it may concern:

Be it known that I, HOWARD ROY STACKS, of Philadelphia, in the county of Philadelphia, and in the State of Pennsylvania, have 5 invented a certain new and useful Improvement in Change-Speed Gearing; and I do hereby declare that the following is a full, clear, and exact description thereof, reference being had to the accompanying drawings, in which—

Figure 1 is a vertical longitudinal sectional view of the change-speed gearing embodying my invention. Figs. 2 and 3 are respectively transverse sectional views, on an enlarged scale, of the gearing shown in Fig. 1, taken, respectively, on the lines 2 2 and 3 3 of Figs. 1 and 2; and Fig. 4 is an end view, on an enlarged scale, with head removed and reversing-gears shown in section.

20 The object of my invention has been to provide a change-speed gearing which shall have, among others, any or all of the following advantages: That of being capable of being contained in a compact casing that can 25 be readily placed in any desired location—as, for instance, upon an automobile—that of being comparatively simple, that of being efficient, that of being capable of producing any desired number of changes of speed, 30 of not requiring great accuracy in its construction, and of having its parts so arranged that they shall be readily accessible without requiring the dismantling of other parts; and to such ends my invention consists in the 35 change-speed gearing hereinafter specified.

In carrying my invention into practice I 40 preferably provide a casing A, which is preferably substantially circular in cross-section and which preferably consists of a body a, having one head a' formed integral therewith. The opposite head a² is preferably removable. In the heads of the casing are formed alining bearings a³ and a⁴, respectively, each of such bearings being closed by 45 term "units," the gearing in one or more of a stuffing-box of any desired construction. The casing contains any desired number of what I which can be employed in such a way that a number of changes of speed can be communicated from the driving-shaft to the driven shaft, which number is usually proportional to the square of the number of units employed. Each unit is mounted upon a separate shaft, the said shafts alining with the

bearings a³ and a⁴. The driving-shaft B is 55 mounted in the bearing a³ in the head a'. The shafts C, D, and E of each of the three units are respectively mounted in brackets F, G, and H, which are preferably of such form as to fit the circular portion of the body 60 A and each of which is provided with a lug f, g, and h, respectively, which receives a cam-shaft I, that is mounted in the lower portion of the frame, the brackets by their engagement with the cam-shaft being prevented 65 from turning in the casing.

The driving-shaft B has keyed to it a gear K and enters the hub l of a friction-disk L, that is also journaled on the shaft C. The friction-disk L is provided with any desired 70 number of bosses l', (preferably three,) each of which is provided with a journal for a spindle M, the said spindle having keyed to one end thereof a pinion N, that meshes with the gear K on the driving-shaft, and having keyed 75 to its other end a gear O, that meshes with a gear P, which latter is keyed to the shaft C. A second friction-disk Q is preferably journaled on a bushing l'', carried by the friction-disk L, and is provided with openings to permit the passage through it of the bosses l'. One of the said bosses is preferably provided with flat radially-extending sides l'', and the disk Q is fitted to said surfaces, so that while the latter disk can move toward and away from 80 the former disk in a direction parallel to the shafts the said disks are caused to rotate together. The hub of the disk Q is provided with a friction-cone q, which is adapted to 85 coact with a complementary friction-cone R, 90 that is secured to the shaft C in any desired manner, as by being screwed to the gear P. A spring S is mounted between the disks L and Q in any desired manner, as within a recess formed in the friction-disk q, so that the 95 said spring tends to move the said disks away from each other. The disks L and Q are provided upon their peripheries with oppositely-inclined conical surfaces l'' and q'', respectively, and friction-bands T and U are provided to coöperate with said surfaces not only to hold the said disks from rotation, but to force them together. The disks T and U are each provided with a V-shaped groove t and u, respectively, which may extend for substantially half a circle to engage the conical surfaces on the peripheries of the friction-disk. Each band is provided with an up-

wardly-extending lug t' and u' , respectively, each of which lugs is adapted to engage a screw t^2 or other stationary but adjustable projection in the upper portion of the casing. 5 The lower ends of the bands T and U are respectively provided with opposite lugs t^3 and u^2 , which are adapted to receive a spring V, that thus tends to move the free ends of the friction-bands away from each other. The 10 band T is provided with an arm t^4 , that extends beneath the lower end of the band U, and a lever W is pivoted upon pins t^5 and u^3 , respectively, which are secured in the ends of the respective friction-bands, so that the tilting 15 of the lever shall tend to draw the bands together against the stress of the spring V and to cause them to embrace the friction-disks. The lever W is provided with an arm w , which is adapted to engage projections x upon cams X, which latter are mounted upon the cam-shaft I, (before mentioned,) so that as a projection x upon the cams rides under the arm w of the lever the friction-bands will be tightened. The projections x upon the 20 cams X of the respective units are so located that any one unit may be caused to operate by itself or that any two or more units may be caused to operate in any desired combination of units. The cam-shaft is journaled in the head a' and in the arms f , g , and h of the brackets F, G, and H, respectively. The cam-shaft is provided with any convenient means for turning it, as with a bevel-gear i , that is engaged by a bevel-pinion i' upon a hollow 25 shaft i^2 , that extends through a stuffing-box in the casing and is provided with a hand-wheel i^3 .

The shaft C is provided upon the end opposite to that next the driving-shaft with a gear 30 Y, corresponding to the gear K on the driving-shaft, and said gear meshes with pinions on the second unit, corresponding with the pinions N on the first unit. Each unit is or may be precisely like the first unit, which has been 35 described in detail, except that the proportion of its pinions to the gears on the shafts is preferably different from that of the other units,) and it will therefore not be necessary to describe in detail the construction of the remaining units. The shaft E of the last unit is provided upon its end opposite the said unit with a bevel-gear Z, which is free to turn 40 upon such shaft and which has a conical friction-surface z , that is adapted to coöperate 45 with one end of a double friction-cone A', the latter being journaled upon the driving-shaft B'. The driving-shaft B' has keyed to it a bevel-gear C', corresponding to the bevel-gear Z, and like such gear is provided with a 50 friction-surface c , that is adapted to coöperate with the double friction-cone A', that is keyed upon the shaft E. A bevel-pinion or bevel-pinnions D' are mounted between the bevel-gears Z and A', the said pinions being 55 mounted in any desired manner, as by studs 60

d, which are mounted in brackets a^5 , formed on the casing-head a^2 . The double friction-cone A' is provided with a neck that is adapted to be engaged by a yoke or yokes E', each of which is swiveled on the shipper-lever F', the latter being preferably fulcrumed on a bracket a^6 on the casing-head a^2 . The lower end of the shipper-lever is provided with a slot f' , which is adapted to be engaged by an eccentric G', formed on the end of a shaft G², that is preferably mounted within the hollow shaft i^2 and is provided with a handle G³, by which it can be turned to cause the double friction-cone to engage either the gear Z or the cone A', as desired. 80

In the operation of the above-illustrated embodiment of my invention the cams X having been provided with the proper number of projections x , properly located, the cam-shaft I is turned to cause, for instance, 85 the friction-bands of the first unit to hold the friction-disks thereof stationary. Motion will then be communicated from the driving-shaft to the driven shaft in the following manner: The gear K will drive the pinion N, 90 which through the spindle M will drive the pinion O. The latter will drive the pinion P, the speed of the latter pinion being dependent upon the proportion of the gearing. The pinion P will be free to revolve independently 95 of the disk Q, because the friction-bands having forced the disk Q against the disk L have withdrawn the friction-cone q from the friction-cone R, compressing the spring S. As the levers W of the second and third units are 100 not engaged by their respective cams, the friction-bands of such units will be forced apart by their springs V, and consequently both friction-disks of both of said units will be free to revolve. Moreover, the springs S 105 of the said units will have forced the cones q thereof into engagement with the cones R under the action of the springs S. The taper of the cones q and R is made such that the friction produced by the pressure of 110 the springs S will be sufficient to cause the cone R to be driven from the cone q without other means of holding the said cones together. Therefore in each of the second and 115 third units the cones q and R will be in engagement with each other, so that all of the alining shafts C, D, and E will be coupled together and the speed of the gear P will be that of the speed of the shaft E, which speed will be 120 communicated directly or reversed to the driving-shaft B', according as the double friction-cone A' is in engagement with the gear Z or with the gear C'. As the gear Y and the gear P of the second unit will be revolved at the same rate of speed, owing to the fact that 125 their respective shafts are coupled together, the pinions N and O of such unit will not revolve upon their axes, but will simply revolve with the disks L and Q without relative rotation. The same state of facts will exist 130

with reference to the third unit or any subsequent unit. If it is desired to drive the driving-shaft at the speed of the second unit instead of the first, the lever W of the second unit is raised by means of its respective cam, causing the friction-bands to embrace and hold the friction-disks L and Q of the second unit, the lever W of the first unit being at the same time released, so that the friction-bands 5 are forced apart and release the disks L and Q of the first unit and leave the spring S thereof free to cause a driving engagement between the friction-cones q and R. Thus the shafts B and C will be coupled together, the shaft D will be driven from the shaft C 10 through the gears and pinions of the second unit, and the shaft E will be coupled to the shaft Y, so that all of the change of speed will be due to the gearing of the second unit. In 15 the same manner by releasing the friction-bands of the second unit and engaging those of the third unit the speed can be varied in proportion to the gearing of the third unit alone. By driving through the gearing of 20 the first and second units the result obtained will be a speed which is the product of the speed of the first unit multiplied by that of the second unit, the third unit being eliminated. In this manner a speed equal to the 25 product of the speeds of any two of the units can be used or to a product of all three units can be obtained, and each of these many speeds can be reversed by movement of the handle G³.

35 It will be observed that my variable-speed gearing has, among others, the following advantages: While giving a large variety of speeds, it is very compact and comparatively simple. It is adapted to be entirely inclosed 40 in a casing, so that such casing can be filled with oil, and the gearing thus operated in a bath of oil.

It is obvious that various changes can be made in the above-illustrated construction 45 which will be within the scope of my invention, and I desire not to be limited beyond the language of my claims and the requirements of the prior art.

Having thus described my invention, what 50 I claim is—

1. In a change-speed gearing, the combination of a driving-shaft, a driven shaft, a train of gears and a reversing means, a cam-shaft, means whereby a cam on said shaft 55 may be caused to connect said first-mentioned shafts through said train of gears or not as desired, said reversing means comprising a double reversed cone-pulley and corresponding clutch members, a lever for shifting 60 said cone to engage either of said clutch members, said lever being provided with a slot, a hollow hand-shaft geared to said cam-shaft, and a hand-shaft concentric with said first-mentioned shaft and having an eccentric-pin 65 to engage said slot and said lever.

2. In a change-speed gearing, the combination of a driving-shaft, a driven shaft, a series of trains of gears, and a reversing means, a cam-shaft, means whereby cams on said shaft may be caused to connect said first-mentioned shafts through either or all of said trains of gears, or not, as desired, said reversing means comprising a double reversed cone-pulley and corresponding clutch members, a lever for shifting said cone to engage either 70 of said clutch members, said lever being provided with a slot, a hollow hand-shaft geared to said cam-shaft, and a hand-shaft concentric with said first-mentioned shaft and having an eccentric-pin to engage said slot and 75 said lever.

3. In a change-speed gearing, the combination of a substantially cylindrical case closed by heads at the opposite ends, alining driving and driven shafts substantially coaxial with said case, a cam-shaft parallel to said first-mentioned shafts, a series of trains of gears, means operated by the cams on said cam-shaft, whereby said driving and driven shafts may be connected or not through any 80 one or more of said trains of gears, a reversing means interposed between said driving and driven shafts, said reversing means comprising a double reversed cone-pulley, female cone-pulleys, each of which is adapted 85 to coact with one end of said cone-pulley, a bearing-lug formed on the adjacent head of said casing, a lever fulcrumed on said bearing-lug, shoes pivoted to said lever and engaging a neck formed on said cone-pulley, concentric hand-shafts, one of which is geared to 90 said cam-shaft, and the other of which is provided with an eccentric-pin engaging a slot in said lever, said female cone-pulleys being provided with gear-teeth, and an idler pinion or pinions meshing with both sets of gear-teeth.

4. In a change-speed gearing, the combination of a driving-shaft, a driven shaft, gears mounted upon each of said shafts, a clutch 100 member secured to one of said shafts, a disk concentric with said shafts and provided with a complementary clutch member and a second disk concentric with said shafts, a spindle or spindles projecting from the opposite faces of 105 said second disk, pinions mounted upon the opposite ends of each of said spindles, which pinions mesh with said first-mentioned gears, means for holding said disks from rotation and means for causing said clutch members to be 110 engaged.

5. In a change-speed gearing, the combination of driving and driven shafts, gears mounted upon each of said shafts, a clutch member on one of said shafts said clutch 115 member being located between said gears, disks concentric to said shafts and located between said gears, a clutch member complementary to said first-mentioned clutch member mounted on one of said disks, pinions 120

130

mounted on the other of said disks which pinions are adapted to transmit motion from one of said gears to the other thereof, means whereby said disks may be held from rotation and means for causing said clutch members to be engaged.

6. In a change-speed gearing, the combination of driving and driven shafts, gears mounted upon each of said shafts, a clutch member mounted upon one of said shafts, said clutch member being located between said gears, disks concentric to said shafts and located between said gears, a clutch member for one of said disks, said clutch member being complementary to said first clutch member, spindles journaled in the other of said disks, pinions mounted upon said spindles upon opposite faces of said disks, said pinions being adapted to transmit motion from one of said 10 gears to the other thereof, means whereby said disks may be held from rotation, and means for causing said clutch members to be engaged.

7. In a change-speed gearing, the combination of driving and driven shafts, gears, one of which is mounted upon each of said shafts, a clutch member for each of said shafts, said clutch members being interposed between said gears, one of said clutch members being movable and having a disk formed thereon or attached thereto, a spring adapted to throw said movable clutch member into operative position, pinions carried by said disk, which pinions are adapted to transmit motion from one to the other of said gears, and means for retracting said clutch member and for holding said disks from rotation.

8. In a change-speed gearing, the combination of a driving-shaft, a driven shaft, a gear and a clutch member mounted upon each of said shafts, a disk, pinions carried by said disk, said pinions being adapted to transmit motion from one to the other of said shafts, one of said disks being provided with a projection and the other of said disks with a slot that is adapted to receive said projection, whereby relative rotary movement is prevented between said disks, means for causing said clutch members to be engaged, and means whereby said disks may be prevented from rotation.

9. In a change-speed gearing, the combination of driving and driven shafts, gears, one of which is mounted on each of said shafts, clutch members interposed between said gears, a disk secured to one of said clutch members, a second disk, pinions mounted on said second disk, said pinions being adapted to transmit motion from one to the other of said gears, one of said disks being provided with a projection and the other of said disks with a slot that is adapted to receive said projection, a spring adapted to cause engagement of said clutch members,

and means whereby said disks may be held from rotation.

10. In a change-speed gearing, the combination of driving and driven shafts, gears, one of which is mounted upon each of said shafts, a clutch member interposed between said gears, a disk secured to said clutch member for operating the latter, a second disk having bosses or projections formed thereon, spindles journaled in said bosses, said first-mentioned disks being provided with openings that are adapted to receive said projections, pinions mounted upon said spindles upon opposite faces of the second-mentioned disk, said pinions engaging said gears, means whereby said disks may be separated to engage said clutch members, and means whereby said disks may be drawn together and held from rotation.

11. In a change-speed gearing, the combination of driving and driven shafts, a gear mounted on each of said shafts, clutch members interposed between said gears, a disk secured to the movable clutch member for operating the latter, a second disk, pinions carried by said second disk and adapted to transmit motion from one to the other of said gears, said disks being provided with opposite conical surfaces, bands provided with V-shaped grooves that are adapted to engage 95 said conical surfaces, and means whereby said bands may be caused to grip said surfaces.

12. In a change-speed gearing, the combination of driving and driven shafts, a gear mounted on each of said shafts, clutch members interposed between said gears, a disk secured to the movable clutch member for retracting the latter, a second disk, a spindle or spindles journaled in said second disk, pinions mounted on said spindles and adapted to transmit motion from one to the other of said gears, a spring interposed between said disks for forcing the movable member of said clutch into engagement, the edges of said disks being provided with oppositely-inclined conical surfaces, and bands having V-shaped grooves that are adapted to engage said surfaces to force said disks together and prevent their rotation.

13. In a change-speed gearing, the combination of driving and driven shafts, gearing for transmitting motion from one to the other of said shafts, said gearing comprising a disk or disks, and means for holding said disk or disks from rotation, said means comprising substantially semicircular friction-bands, one of such bands being provided with an L-shaped end, a lever pivoted to the ends of said bands, said bands being provided with opposing pins, and a spring mounted upon said pins for separating said bands.

14. In a change-speed gearing, the combination of a substantially cylindrical casing, driving and driven shafts having bearings in

the opposite ends of said casing, one end of said casing being removable, a series of units of change-speed gearing, each of which has connection with said shafts or with another 5 of said units, said connections permitting disconnection simply by movement in the direction of the axes of said shafts, a cam-shaft for operating said change-speed gearing, and bearing-brackets fitting the bore of 10 said casing and provided with lugs for engagement with said cam-shaft, whereby the necessity for fastening said bearing-bracket to said casing is avoided.

15. In a change-speed gearing, the combination of driving and driven shafts, gearing for transmitting motion from one to the other

of said shafts, said gearing comprising a disk or disks, and means for holding said disk or disks from rotation, said means comprising substantially semicircular friction-bands, one 20 of such bands being provided with an L-shaped end, a lever pivoted to the ends of said bands, said bands being provided with opposing pins, and a spring mounted upon said pins for separating said bands and a reversing-gearing.

In testimony that I claim the foregoing I have hereunto set my hand.

HOWARD ROY STACKS.
